UNITED STATES PATENT OFFICE.

LEO J. O'RILEY, OF GRAND RAPIDS, MICHIGAN.

PHONOGRAPH.

1,303,951.

Specification of Letters Patent.

Patented May 20, 1919.

Application filed October 23, 1918. Serial No. 259,343.

To all whom it may concern:

Be it known that I, LEO J. O'RILEY, a citizen of the United States, residing at Grand Rapids, county of Kent, State of Michigan, have invented certain new and useful Improvements in Phonographs, of which the following is a specification.

This invention relates to improvements in phonographs.

10 The main objects of this invention are:

First, to provide an improved phonograph by which all tones are very accurately reproduced.

Second, to provide an improved phonograph in which the tones produced are of great carrying power and at the same time without harshness or mechanical sound.

Third, to provide an improved horn for phonographs.

20 Further objects, and objects relating to structural details, will definitely appear from the detailed description to follow.

I accomplish the objects of my invention by the devices and means described in the following specification. The invention is clearly defined and pointed out in the claims.

25 A structure which is a preferred embodiment of my invention is clearly illustrated in the accompanying drawing, forming a part of this specification, in which:

Figure I is a vertical central section on a line corresponding to line 1—1 of Fig. II of a structure embodying the features of my invention, the tone arm, record and parts of the motor being shown in full lines and more or less conventionally.

Fig. II is a horizontal section on a line corresponding to line 2—2 of Fig. I.

30 Fig. III is an enlarged detail vertical section through the motor board and the end of the horn on a line corresponding to line 3—3 of Figs. I and II.

Fig. IV is a detail section on a line corresponding to line 4—4 of Fig. II, showing details of the sounding board.

Fig. V is a detail front elevation showing the sound opening and the relation of the mouth of the horn thereto.

Fig. VI is a detail plan view of the horn as it would appear extended or straight, showing the arrangement of the top wall parts.

Fig. VII is a detail bottom view of the horn as it would appear extended or straight,

showing the arrangement of the bottom wall parts.

Fig. VIII is a detail longitudinal section through the top wall of the completed horn on a line corresponding to line 8—8 of Fig. VI.

In the drawing similar reference characters refer to similar parts throughout the several views, and the sectional views are taken looking in the direction of the little arrows at the ends of the section lines.

Referring to the drawing, the cabinet 1, illustrated, is made up of suitable corner posts, cross pieces and panels. As these details form no part of my present invention they are not further described herein. The 70 cabinet has a hinged top 2 affording access to the record table 3 and tone arm 4 which may be of any suitable structure.

The motor, shown conventionally at 5, is mounted on the under side of the motor 75 board 6. The motor board 6 has an opening 7 therein with which the tone arm registers and below this opening is a block 8 having an opening therein registering with the opening 7.

My improved horn comprises an outwardly flared bell portion and a curved neck portion. The horn is provided with a flange 9 at the end of its neck which is secured to the block 8 on the motor board by means of 85 the screws 10 so that the horn is rigidly mounted by means of the flange.

A rubber gasket 11 is arranged between the flange and its support to prevent transmission of vibrations of the motor board to 90 the horn.

The sounding board 12 is mounted in the cabinet in a spaced relation to the motor board, providing a chamber for the horn, the sound board constituting the bottom of 95 this chamber. The sounding board is supported at its front and rear ends only,—see Figs. II and IV. Below the sounding board is a dead air chamber 13, the sounding board constituting the top of this dead air chamber. 100

The sound opening 14 of the cabinet is, in the structure illustrated, provided with an ornamental grid 15. The horn is supported with its end close to this sound opening, the 105 sound opening, however, being of less dimension than the diameter of the mouth of the horn so that the edges of the sound

opening project in front of the edges of the horn about a quarter of an inch as shown in Fig. I. Both the bell portions and the neck portions of the horn are preferably 5 rectangular as illustrated.

The side walls 16 of the bell and neck portion of the horn are formed of soft open grained wood disposed with the grain longitudinally of the horn as indicated in Fig. 10 I. Each side wall is preferably formed integrally of a piece of board cut wood. The top and bottom walls are formed of sections, the outer sections 17 and 18, respectively, extending substantially to the curve of the horn. These outer sections are also formed of soft open grained wood disposed with the grain longitudinally of the horn. The curved neck portions of the top walls, in the structure illustrated, are formed of relatively short sections 19, 20, 21 and 22, while the curved bottom wall is formed of relatively short sections 23, 24 and 25, the sections being disposed edge to edge and rigidly secured by glue, the edges being preferably beveled as shown in Fig. VIII. These short sections are formed of soft open grained wood and hard close grained wood disposed alternately with the grain of the wood diagonally and the grain of adjacent 30 sections alternating in direction as indicated in Figs. II, VI and VII. With the sections as shown in the drawing the sections 19, 21 and 24 are of soft wood and the sections 20, 22, 23 and 25 are of hard wood. 35 I also provide the horn with a coating 26,—see Fig. VIII, of hard varnish gums laid on so as to provide a substantially thick body at the curve of the neck tapering or diminishing in thickness toward each end of 40 the horn. This coating is formed by cutting the gum with an alcoholic spirit sufficient to permit its being applied in repeated coats to build up the substantial body as indicated and to thin it down toward each end into 45 the varnishing coat with which the bell of the horn is preferably provided.

A hollow wood straight grain post 27 is arranged within the horn resting upon the bottom wall section 18 and engaging the top 50 wall at the inner end of the outer top wall section 17.

I also provide a sound, straight grain post 28 which rests on the sounding board centrally above the dead air chamber 13 and 55 engages the horn at the rear end of the bottom wall section 18. This sound post is not designed as a support for the horn, which is, as stated, rigidly mounted by means of its flange 9. The sound post being engaged 60 with the horn sufficiently to maintain it in position and perform its function would, of course, serve in a measure as a support, but the horn is rigidly supported when this post is removed.

65 The post within the horn is found to ma-

terially improve the same. My improved instrument is highly satisfactory and reproduces or develops clear tones of the human voice or any instrument without developing unnatural or mechanical sounds.

I have not attempted to set forth herein my theory of the action of the various elements or their combined action whereby the results stated are reproduced, as such theory seems unimportant to an understanding of 75 and the practical application of my invention.

I have illustrated and described in detail one satisfactory embodiment of my invention. I do not illustrate or describe other 80 embodiments or adaptations as I believe they will be readily understood by those desiring to utilize my improvements.

Having thus described my invention, what I claim as new and desire to secure by Letters Patent, is:

1. A phonograph horn comprising an outwardly flared bell portion and a curved neck portion both of rectangular cross section, the side walls of the bell and neck portions being integral and formed of soft open grained wood disposed with the grain longitudinally of the horn, the top and bottom walls being formed of sections, the outer sections extending substantially to the curve of the horn and being of soft open grained wood disposed with the grain longitudinally of the horn, the curved neck portions being formed of relatively short sections of soft open grained wood and hard close grained wood disposed alternately with the grain of the wood diagonally and the grain of adjacent sections 90 alternating in direction, the inner section of the top wall being of soft wood and the inner section of the bottom wall being of hard 95 wood, the sections joining said outer sections being of hard wood, the several sections being glued edge to edge.

2. A phonograph horn comprising an outwardly flared bell portion and a curved neck 110 portion both of rectangular cross section, the side walls of the bell and neck portions being integral and formed of soft open grained wood disposed with the grain longitudinally of the horn, the top and bottom walls being 115 formed of sections, the outer sections extending substantially to the curve of the horn and being of soft open grained wood disposed with the grain longitudinally of the horn, the curved neck portions being 120 formed of relatively short sections of soft open grained wood and hard close grained wood disposed alternately with the grain of the wood diagonally and the grain of adjacent sections alternating in direction, the inner section of the top wall being of soft 125 wood and the inner section of the bottom wall being of hard wood, the sections joining said outer sections being of hard wood, the several sections being glued edge to edge,

and the neck portion being coated with a gum applied so that there is a body of gum of substantial thickness at the curve of the neck lapping onto the bell and gradually decreasing in thickness toward each end.

3. A phonograph horn comprising a bell portion and a neck portion, the side walls of the bell and neck being of soft open grained wood disposed with the grain longitudinally of the horn, the top and bottom walls being formed of alternating sections of soft open grained wood and hard close grained wood, the bell wall sections being of soft wood disposed with the grain longitudinally of the horn, the neck sections being relatively short and disposed with the grain of the wood diagonally and alternately, the several sections being glued edge to edge.

4. A phonograph horn comprising a neck portion, the side walls of the bell and neck being of soft open grained wood disposed with the grain longitudinally of the horn,

the top and bottom walls being formed of alternating sections of soft open grained wood and hard close grained wood, the bell wall sections being of soft wood disposed with the grain longitudinally of the horn, the neck sections being relatively short and disposed with the grain of the wood diagonally and alternately, the several sections being glued edge to edge, and the neck portion being coated with a gum applied so that there is a body of gum of substantial thickness at the curve of the neck lapping onto the bell and gradually decreasing in thickness toward each end.

In witness whereof, I have hereunto set my hand and seal in the presence of two witnesses.

LEO J. O'RILEY. [L. s.]
